DESIGN FOR A COMBINED FLATIRON HANDLE AND SUPPORT

Semjon Krasnikov, Chicago, Ill.

Application April 27, 1940, Serial No. 92,001

Term of patent 3½ years

To all whom it may concern:

Be it known that I, Semjon Krasnikov, a citizen of Estonia, residing at Chicago, in the county of Cook and State of Illinois, have invented a new, original, and ornamental Design for a Combined Flatiron Handle and Support, of which the following is specification, reference being had to the accompanying drawing, forming part thereof.

Fig. 1 is a side elevational view of a combined flatiron handle and support showing my new design;

Fig. 2 is an end elevational view thereof;
Fig. 3 is a top plan view thereof; and
Fig. 4 is a top plan view of the support portion of the handle shown in Figs. 1, 2 and 3.

I claim:

The ornamental design for a combined flatiron handle and support, substantially as shown.

SEMJON KRASNIKOV.
